UNITED STATES PATENT OFFICE.

HENRI HAROLD MUIRHEAD, OF BLOOMSBURG, PENNSYLVANIA.

COOKY CUTTER.

Application filed May 26, 1924. Serial No. 715,890.

To all whom it may concern:

Be it known that I, HENRI HAROLD MUIRHEAD, a citizen of the United States, residing at Bloomsburg, in the county of Columbia, State of Pennsylvania, have invented a new and useful Cooky Cutter; and I do hereby declare the following to be a full, clear, and exact description of the invention, such as will enable others skilled in the art to 10 which it appertains to make and use the same.

The invention relates to cooky cutters and has for its object to provide a device of this character comprising an annular body 15 member, in which a plunger disc is disposed and held by means of a coiled spring surrounding a shaft carried by the disc and guidable in a U-shaped bracket carried by the body member. Another object is to provide a U-shaped bracket with a sleeve surrounding the shaft, and the upper end of the shaft with a sleeve telescopically engaging the first mentioned sleeve and within 20 which sleeve the coiled spring is housed and 25 protected from dirt and foreign matter.

A further object is to provide an ejecting disc of slightly less diameter than the chamber of the body member, thereby preventing scraping or sticking of the disc in relation 30 to the wall of the body member, and to provide telescopically engaged sleeves for guiding the shaft during an ejecting operation and maintaining the disc in axial relation 35 to the chamber of the body member during an ejection operation.

With the above objects in view the invention resides in the combination and arrangement of parts as hereinafter set forth, shown in the drawing, described and 40 claimed, it being understood that changes in the precise embodiment of the invention may be made within the scope of what is claimed without departing from the spirit of the invention.

45 In the drawing:—

Figure 1 is a vertical transverse sectional view through the cooky cutter.

Figure 2 is a top plan view of the cutter.

50 Figure 3 is a large perspective view of the handle member of the device.

Referring to the drawing, the numeral 1 designates the body member of the cutter, which body member is preferably annular shaped as shown, and is provided with a 55 horizontally disposed flange 2, to the upper side of which is secured by means of rivets

3, a U-shaped handle 4, under which the fingers of the operator may be placed during a cooky ejecting operation after a cooky has been cut by the body member 1. Although the handle member has been described as connected to the flange 2 by means of rivets 3, it is to be understood that it may be joined to the flange 2 by soldering or any other suitable manner. Disposed within the chamber 5 of the body member 1 is an ejecting disc 6, which disc is of less diameter than the diameter of the chamber 5, and consequently during an ejecting operation, if the disc 6 is maintained in axial relation with the body member 1, said disc will not engage the inner periphery of the body 1, consequently sticking or scraping of the disc is obviated. Disc 6 is provided with an upwardly extending shaft 7, which extends 70 through an enlarged aperture 8 in the handle member 4, and axially through the sleeve 9 carried by the handle member, and the sleeve 10 carried by the knob 11 on the upper end of the shaft, said sleeves telescopically engaging each other, and form means for axially guiding the shaft and disc during an ejecting operation after cutting a cooky disc. During the operation of the device, the operator places two or more fingers 75 under the bracket 4 and places a finger on the knob 11, forces the same downwardly to the dotted line position shown in Figure 1, against the action of the coiled spring 12, which is entirely housed within the sleeves 80 9 and 10 and interposed between the handle member 4 and the knob. It will be seen that when pressure is relieved from the knob 11, that expansive action of the coiled spring 85 12 will return the disc 6 to inoperative position as shown in Figure 1, however during the axial movement upwardly and downwardly of the shaft 7, the telescopically engaged sleeves 9 and 10 will axially guide the shaft and disc 6 for preventing engagement 90 of the periphery of the disc 6 with the wall of the chamber 5. It will also be seen that the spring 10 is entirely housed, consequently the collection of dirt therein, which will render the device unsanitary is obviated.

The sleeve 9 is preferably secured to the handle member 4 by soldering the same thereto as at 13, however it is to be understood that it may be secured to the handle member in any suitable manner.

110 From the above it will be seen that a cooky cutter is provided whereby cookies

may be easily and quickly formed from a piece of dough and ejected from the cutter by the disc 6 after each cutting operation thereby obviating the shaking of the device 5 as is now the custom with cooky cutters having no ejecting mechanism. It will also be seen that the spring 12 is entirely housed and the sleeves 9 and 10 not only house the spring, but also form guiding means for the 10 shaft 7 and the disc 6.

The invention having been set forth what is claimed as new and useful is:—

15 A cooky cutter comprising a chambered body member, a disc disposed within the chamber of the body member and spaced from the wall thereof, a U-shaped handle member carried by the body member, a shaft carried by the disc and extending through an enlarged aperture of the handle member, 20 a knob threaded on the upper end of the

shaft, a sleeve carried by said knob and disposed in an annular channel of the knob, said knob carried sleeve telescopically engaging a sleeve rigidly carried by the center of the handle member and surrounding the aperture therein, a coiled spring surrounding the shaft and disposed within the sleeves and entirely housed thereby, said sleeves forming sole means for axially guiding the shaft and disc during a cooky ejecting operation and maintaining the disc in spaced relation to the wall of the chambered member. 25

30 In testimony whereof I have signed my name to this specification in the presence of two subscribing witnesses.

HENRI HAROLD MUIRHEAD.
